DESIGN FOR A COAT

Jacob A. Silverman, New York, N. Y.

Application December 13, 1937, Serial No. 73,576

Term of patent 3½ years

To all whom it may concern:

Be it known that I, Jacob A. Silverman, a citizen of the United States of America, residing in New York city, in the Borough of Manhattan, county and State of New York, have invented a new, original, and ornamental Design for a Coat, of which the following is a specification, reference being had to the accompanying drawing, forming part thereof, wherein,

The design is characterized by the open fur trimmed collar with strap and leather hook closing, and the specific double lapels shown, in combination with the coat disclosed.

I claim:

The ornamental design for a coat, substantially as shown and described.

JACOB A. SILVERMAN.
